(57) **CLAIM**

We claim the ornamental design for an extendable fork, substantially as shown and described.

DESCRIPTION

FIG. 1 is a perspective view of an extendable fork in a nested position in accordance with the present design.

FIG. 2 is a top view of the extendable fork in the nested position.

FIG. 3 is a back view of the extendable fork in the nested position.

FIG. 4 is a left side view of the extendable fork in the nested position.

FIG. 5 is a right side view of the extendable fork in the nested position.

FIG. 6 is a head end view of the extendable fork in the nested position.

FIG. 7 is a handle end view of the extendable fork in the nested position.

FIG. 8 is a perspective view of the extendable fork in an extended position.

FIG. 9 is a bottom view of the extendable fork in the extended position.

FIG. 10 is a perspective view of the fork element alone of the extendable fork.

FIG. 11 is a front perspective view of the handle alone of the extendable fork; and,

FIG. 12 is a back perspective view of the handle alone of the extendable fork.

The broken lines are shown for illustrative purposes only and form no part of the claimed design.

1 Claim, 11 Drawing Sheets
